UNITED STATES PATENT OFFICE.

EDWARD F. SHELLABERGER, OF DE KALB, ILLINOIS.

SHIFTING MECHANISM FOR WEAVING-MACHINES.

SPECIFICATION forming part of Letters Patent No. 613,398, dated November 1, 1898.

Application filed May 26, 1898. Serial No. 681,772. (No model.)

To all whom it may concern:

Be it known that I, EDWARD F. SHELLABERGER, of De Kalb, in the county of De Kalb and State of Illinois, have invented certain new and useful Improvements in Geared Shifting Mechanism for Weaving-Machines, of which the following is a specification.

This invention relates to weaving-machines, and is particularly applicable to wire-weaving machines such as are employed in making wire fencing; but the shifting mechanism of my invention may be employed for other purposes than in the making of fence fabric—as, for example, in covering wires with an insulating material wherein the covering is braided—and this invention is therefore designed to cover said shifting mechanism broadly.

My invention also includes the combination, with this shifting mechanism, of certain weaving mechanisms peculiar to those machines which are employed for producing woven fabric, such as wire fencing, and therefore some of my claims relate to said combinations.

In the accompanying drawings I have shown my invention as applied in a wire-weaving machine for making wire fabric such as is used in fencing.

In said drawings, Figure 1 is a side elevation of the machine as a whole, omitting only from the view the spools which carry the mesh or web wire. Fig. 2 is a partial plan view. Fig. 3 is an enlarged sectional elevation on the line 3 3 of Fig. 1, looking in the direction of the arrows, the gears showing mainly in dotted lines. Fig. 4 is a transverse sectional elevation of the parts shown in Fig. 3, some of the parts being shown in full elevation. Fig. 5 is a diagrammatic view showing the geared shifting mechanism. Fig. 6 is an elevation on the line 6 6 of Fig. 1, looking in the direction of the arrows. Fig. 7 is a cross-section, on the line 7 7 of Fig. 6, through the coiling mechanism and the driving-shaft. Fig. 8 is a series of diagrammatic views showing the shifting mechanisms in various positions. Fig. 9 is a view of one form of the product.

The complete apparatus which is illustrated in the drawings comprises distinct groups of mechanisms for holding the mesh or web

wires and the strand or parallel wires, for shifting the web-wire from one strand to the next adjacent strand and carrying the web-wire around the strand-wire after each shift, split twister-heads for coiling the web-wires and strand-wires together, and a pull-out mechanism for withdrawing the completed fabric.

In the drawings let 10 denote a bed-frame having standards 11, connected by the channel-bars 12, forming the supports for the gears of the shifting mechanism. These channel-bars, as shown, are four in number between each pair of standards and support bearing-plates 13, affording bearings 14 for the spools 15. These spools are arranged parallel to each other, and as many will be provided as there are strand-wires or longitudinal elements or members of the fabric to be woven.

16 represents the wire coiled upon said spools, one end thereof being led forward to the twisting mechanism, hereinafter described.

17 represents the web or mesh wires of the fabric, and these wires are led from suitable spools or reels, not shown, but which will be located in or on the rear of the machine. These web-wires are for a fence fabric of the kind shown one less in number than the strand-wires, and, as will be seen by reference to Fig. 9, each mesh or web wire is carried back and forth between two adjacent strand-wires, being coiled therewith or there-around at the points of intersection. As shown, two and a half coils are formed; but the number of coils or turns and the number of mesh and strand wires and the width of the fabric may be varied at will.

The chief feature of my invention is to provide a reliable mechanism for shifting the web or mesh elements from one of the strand elements to another. In the particular fabric which I have illustrated the mesh-wire is shifted back and forth between adjacent strand-wires; but in some cases it may be desirable to shift the web or mesh wires entirely across the width of a flat fabric or entirely around a tubular fabric. My geared shifting mechanism includes a series of carriers, preferably spur-gears with their teeth enmeshed, so that the adjacent carriers rotate in unison, but in opposite directions.

Acting in conjunction with said carriers, which engage at their peripheries the wires or other strands to be shifted and retain them during one or more complete revolutions, are a series of revolving cams and a series of gear-wheels for operating said cams and preferably rigidly secured therewith, said carriers and cams, with their gearing, constituting the essential features of the shifting mechanism. The carriers are marked 18 and are preferably in the form of spur-gears with peripheral notches 18^a, provided by omitting or mutilating a tooth or teeth. These carriers are arranged in two parallel rows, one row between each pair of standards, and are mounted upon journals 19, which may be rigid with the journals of the spools 15, the journals 19 being mounted within the bearings 14. There will be as many of these carriers 18 as there are strand-wires, and each carrier has loosely mounted upon its axis a gear 20, having a fewer number of teeth than the carriers. In the particular construction shown the carriers have twenty-eight teeth and the gears twenty-four teeth.

21 represents cams in the form of flat disks secured rigidly with the gears 20 and located between them and the carriers. The cams through about half of their circumference correspond substantially with the pitch-line of the teeth of the carriers 18, projecting beyond the teeth of the gears 20, the remaining portion of the cam being below the extremities of said gear-teeth, or the cam may be semi-circular in outline. The web-wires are for convenience and to prevent their becoming tangled threaded through the pipes 22, these pipes being long enough to extend from one set of carriers to the other and parallel to the spools carrying the strand-wires. These pipes are received in the notches or recesses of the carriers and during the rotation of the latter will obviously be carried around the axis of the spools. In order to shift the pipes from one carrier to the next, the cams are employed, and to secure this shifting at the proper time the gears 20 are driven so as to perform a definite number of revolutions with relation to the revolution of the carriers. Thus, assuming that the pipes can only be shifted from one carrier to the other, when the pipe held in one carrier shall come opposite the notch or recess of an adjacent carrier the cam and gear must be so driven as that the former shall engage the pipe at the proper time and shift it from one carrier to the adjacent one. The number of revolutions of the gear 20 relative to that of the carrier will depend upon the number of complete turns which it is desired the wire carried by the pipe shall perform about the wire carried by the spool turning with the journal of the carrier. As the machine illustrated in the drawings is organized it is desired to turn the web-wires three times around the strand-wires, and therefore the cam-gear is so driven that it will perform three and one-half revolu-

tions to three revolutions of the carrier, and consequently each pipe, after being carried around the spool three times, will be shifted, 70 when in line with the axis of the gears, to the next adjacent carrier, and after performing three revolutions therewith will be shifted back to the first carrier, and so on alternately back and forth between adjacent carriers. 75

By reference to Fig. 8 the initial and intermediate and final positions are shown in diagrammatic views, the gears 20 being omitted in these figures to secure clearness of illustration. The first position shows the mechanism just as the pipes are about to be shifted from one carrier to the other. In this, which is called the "initial" position, the cam is in contact with the pipes, the pipes being nearly in line with the axis of the carriers. As the 80 cams turn in the direction indicated by the arrows their points pass through the plane of the axis of the carriers, and during such passage the pipes are shifted from one carrier to the next. The cam in effecting the shifting 85 of the pipe is moving at a greater rate of speed than the carrier, and therefore by the time the cam has shifted the pipe it has also covered the recess of the carrier from which the pipe is shifted. The next position shown 90 in said figure is that in which a complete revolution of the carrier has been performed, the cam having made more than one complete revolution and still covering the recess of the carrier, and the recess will likewise be closed 95 at the end of the second revolution; but the cam will be advanced. The third position shown is that wherein the carrier has nearly completed three revolutions, and in that position the cam has nearly completed three 100 and one-half revolutions, the recesses being nearly in line with the axis and uncovered. The fourth position shows the pipes returned 105 into the initial carriers by means of the cams on the adjoining carriers. As such adjacent 110 carriers turn in opposite directions, it is obvious that the direction of movement of the pipe will change with each shift. If, however, it were desired to turn the web-wires only twice around the strand-wires, the cam-gear would perform two and one-half revolutions while the carrier was performing two 115 revolutions, and if it were desired to shift the web-wires from one carrier to the next throughout the series—as, for example, when 120 said carriers were arranged in circular series and it were desired to shift the web-wires from one to the other completely around the circle—then the cam-gears would perform an equal number of revolutions with such carriers. 125

As a convenient means of driving the carriers and cams I may employ any suitable gear-train. As shown, the power is taken from the main driving-shaft 23, which through the 130 bevel-gears 24 25 drives a series of short cross-shafts 26, having their bearings on the bed-frame and carrying the large gears 27, enmeshed with the idlers 28, which mesh with

the teeth of the carriers 18, the latter enclosing with and driving the gears 29. The gears 29 are loose upon their journals 30 and drive, through the slot-and-pin connection 31 5 32, the gears 33, whose journals 34 are eccentric to the journals 30. The gears 29 33 have the same pitch diameter; but by reason of their eccentric arrangement the gears 33 are enabled to mesh with the cam-gears 20, so as 10 to drive the latter. Two of the teeth of the gear 33 are omitted, as shown in Fig. 5, to permit them to pass the pipes 22, and as the movements of the gears 33 are irregular these mutilations are not diametrically opposite 15 each other. Obviously as the gear 29 turns it will drive the gear 33 faster at one period of its revolution than at another, and this will impart the like irregular rotative movement to the gear 20, thus accelerating the 20 speed of the gear 20 at that point in its revolution where its cam engages the pipe and thereby effecting a quick shifting of the pipe from one carrier to the other. The particular means by which this variation of speed is 25 obtained in the present instance is the slot-and-pin connection, the gears 29 and 33 being mounted upon different centers and connected by means of the pin and slot. It is obvious that the pin 32 will travel in the slot 30 31 as the gears rotate and that as the pin moves toward the inner end of the slot the speed of the gear 33 will be accelerated, and this acceleration is imparted to the gear 20 at the proper time to cause said last-mentioned 35 gear to engage and shift the pipe from one carrier to the other while traveling at its highest rate of speed. This quick shifting of the pipe is desirable in order to insure its entering the notch of the adjacent gear and preventing its being caught or jammed between 40 the gear-teeth.

It will be understood that the shifting mechanism in the illustration shown is duplicated at each end of the spools carrying the strand-wires for the reason that it is desired to employ a long spool, so as to hold a considerable quantity of wire. If, however, the spools were short, then a single series of carriers would be sufficient.

50 The foregoing describes the operation of the shifting mechanism, and it will be understood that said shifting mechanism may be employed for a variety of purposes and with coiling mechanism of various kinds. I have 55 shown a coiling mechanism which is peculiar in some respects and principally in its combination and co-operation with the shifting mechanism. Said coiling mechanism is arranged at the front of the machine and comprises, essentially, a series of split twister-heads, by which is meant that the twisters or coiling mechanisms are constructed in two sections, being divided in planes parallel to their axis of revolution, and the upper sections or members of these split twister-heads being adapted to be shifted laterally and to form successive matching relation with the

lower sections. The shifting sections of the twister-heads carry the mesh-wires, while the non-shifting sections carry the strand-wires, 70 and after each shift the sections are brought into matching relation and rotate, thereby coiling the mesh-wires and strand-wires together. The twister-heads of course perform the same number of revolutions as the mesh-wires perform about the strand-wires, and hence the twister-heads are geared with a definite relation to the operation of the shifting mechanism itself. Thus I have described the shifting mechanism as organized to carry 75 the mesh-wires three times about the strand-wires, and the twister-heads will therefore perform three revolutions between each shift. As the shifting mechanism operates without loss of time and as it requires a certain interval of time to shift the movable sections of the twister-heads, I arrange the gearing so that the twister-heads shall complete three revolutions in one-half the time required to complete three revolutions of the carriers, 80 85 and therefore the twister-heads must rotate at twice the speed of the carriers. It is in this arrangement and combination of gearing that the novelty of this part of the invention consists.

90 Referring again to the drawings, and particularly to Figs. 1 and 6, 35 represents the uprights or end pieces of a framework for supporting the twister-heads or coiling mechanism, these end pieces being connected by 95 top plate 36. A transverse girder or bed 37 supports bearings 38 for the lower sections 39 of the split twister-heads. These split twister-heads have extended journals and are each provided with a longitudinal aperture 40, through which the strand-wire 100 105 110 passes. The upper sections 41 of the twister-heads have the longitudinal apertures 42 for the passage of the mesh-wires, and the sections 41, with their half-boxes, are spanned by the shifting-bar 43, having a connection through the pitman 44 with the eccentric 45, mounted upon a shaft 46 and driven through the bevel-gears 47 48, the latter being mounted upon the shaft 49, driven through shaft 50 115 120 125 from the main driving-shaft 23. The gear 48 is mutilated or provided with gear-teeth on a portion only of its circumference, so that while its driving-shaft runs continuously the pitman is only operated while the teeth of said gear are in mesh with the teeth of the gear 47. By this arrangement the shifting of the twister-heads occupies one half of the time and the rotating of the twister-heads an equal space of time. The rotation of the twister-heads is effected through a suitable train of gearing. (Shown in Fig. 6.) 51 represents a split gear formed as a part of the split twister-heads and adapted to rotate the twister-heads when said gear-sections and the twister-head sections are in matching relation. The gears 51 are driven from the gears 52 and the latter from the large gears 53, the latter having a set of bevel-gear teeth 54, driven by the bevel-

gear 55 on the shaft 56, this shaft being driven from the shaft 57, receiving power from the main driven shaft 23. Each of the gears 53 drives two adjacent twister-heads, an idler 58 being interposed between the gear 53 and the gear 52 for driving one twister-head, so as to reverse the direction of rotation. The bevel-gears 55, which drive the large gears 53, are adjustably mounted on boxes keyed fast 10 on shaft 56.

It has been seen that the carriers 18 rotate constantly and the twister-heads rotate intermittently. To provide for this intermittent rotation, the shaft 57 is driven through a 15 bevel-gear 59 and a mutilated gear 60, so that said shaft and the train of gears imparting motion to the twister-heads has periods of rest equaling its periods of rotation and alternating therewith. During the periods of 20 rest the shifting of the upper sections of the split twister-heads occurs and the gearing is so proportioned that the twister-heads rotate at twice the speed of the carriers, thus forming the same number of coils as the carrier 25 performs revolutions between the shifting operations. As the carriers run constantly, the web-wire will of course be carried around the strand-wires and will become slack thereon. To prevent the tangling of the two wires between 30 the shifting mechanism and the coiling mechanism, the strand-wires are carried through tubular guides 61.

The completed fabric is shown at 62. It is withdrawn from the machine by means of a 35 suitable pull-out, which in the present instance consists of a shaft 62^a, having toothed or notched disks 62^b, which engage the mesh of the fabric. From this pull-out the fabric passes down under the drum 63, thence over 40 the drum 64, and thence back under shaft 65 to the spool or reel 67. The latter is driven from a pulley 63^a on the shaft 63^b, carrying drum 63, by a belt 63^c, having a tension device 68 applied thereto. This mechanism is 45 all driven from the shaft 69 through gears 69^a 69^b, the latter being mounted on shaft 63^b, the drums 63 and 64 being directly geared together. The pull-out may, however, be directly and positively driven; but, as above 50 described, it serves to engage the mesh of the fabric and insures its being drawn out evenly and without distortion.

My invention has numerous advantages, among which the following may be mentioned, 55 while others are obvious:

First. It is necessary in this class of machinery, which runs at a high rate of speed, to have the shifting and coiling mechanism operate with great accuracy. To attain this, 60 I preferably gear all of the carriers throughout the series so that they will perform their revolutions in exactly equal times.

Second. I prefer to drive the cams which effect the shifting at a variable rate of speed, 65 as thereby the shifting may be performed quickly and certainly, and I am also enabled by employing a differential gearing to cover

the recesses in the carriers, and thereby prevent the shifting except at the proper times.

Third. The wire holders or spools of these 70 weaving-machines usually carry a considerable load of wire, and this load varies as the weaving progresses, and as the spools are usually carried around the strand-wires this load imposes considerable strain upon the 75 machinery and consumes power, besides necessitating heavy construction. In my construction the spools are not carried around the strand-wires, but instead thereof carry the strand-wires, and the web or mesh wires 80 are passed around them by the pipes. By employing two rows of carriers and cams placed parallel to each other, but at a considerable distance apart, I am enabled to interpose long spools carrying a large quantity of wire 85 and yet to pass the web or mesh wires around the strand-wires.

Fourth. It is desirable that the wire-holders and shifting mechanism shall run constantly, as otherwise injurious shocks would 90 be occasioned by stopping and starting the holders, loaded as they are with a heavy mass of wire.

Fifth. It is likewise essential that the coiling mechanisms shall have periods of rest to 95 enable the shifting thereof, so that the web-wires may be alternately coiled with adjacent strand-wires. To accomplish this last-named object, the coiling mechanism is run out twice the speed of the carrying and shifting mechanism, but is in motion only one-half of the time.

I wish it to be understood that my invention is not limited in its broadest scope to the particular mechanisms herein shown and described nor to the particular uses herein specifically mentioned, and that changes may be made in the structural features thereof, and particularly in the gearing for driving the essential operating parts, without departing from the scope thereof.

I claim—

1. In a shifting mechanism the combination with the revolving carriers adapted to engage a wire, rod, strand or equivalent fabric element, or its holder, and carry the same in a circular path around the axes of such carriers, of revolving cams for shifting or transferring such wire, &c., or its holder from one carrier to another, and suitable gearing for 110 driving said carriers and cams in due order and relation, substantially as described.

2. In a shifting mechanism, the combination with a series of revolving carriers, having peripheral notches or openings adapted to receive or engage a wire, rod, strand or equivalent fabric element or its holder, and to carry the same in a circular path about the axes of the carriers, of a series of cams, one for each carrier and mounted to revolve about the 125 carrier-axes, said cams having peripheral portions adapted to prevent the passage of the element to be transferred or shifted from one carrier to another during a portion of their 130

revolution and to cause such shifting or transfer during another portion of their revolution, substantially as described.

3. In a shifting mechanism, the combination with a series of revolving carriers having peripheral notches or recesses adapted to receive or engage a wire, rod, strand or equivalent fabric element and to carry the same in a circular path around the axes of such carriers, of a revolving cam mounted to revolve upon an axis coincident with that of the carrier and having peripheral portions adapted to cover said notches and other portions extending radially beyond the bottoms of such notches, and gearing for driving said carriers and said cams differentially, whereby the parts to be shifted may rest in said notches and be ejected therefrom, substantially as described.

20 4. In a shifting mechanism, the combination with a series of rotary carriers having peripheral geared teeth, with notches or openings between some of said geared teeth adapted to receive a strand of a fabric element, or its holder, said carriers being so disposed that their notches will register at one or more points during their revolution, of a series of cams having rotation upon axes coincident with the axes of the carriers, said cams having peripheral portions projecting beyond the bottoms of said notches, gears for rotating said cams, and means for driving said cam-gears and said carriers at different rates of speed, whereby the fabric element may be shifted from one carrier to the next adjacent carrier after performing one or more complete revolutions and a partial revolution about the axes of the latter, substantially as described.

5. In a shifting mechanism, the combination with a series of revolving carriers, having their axes parallel and the said carriers being provided with peripheral notches or recesses to receive a wire, rod or equivalent fabric element, said carriers being geared to rotate in equal times, of a series of cams rotatably mounted upon axes coincident with those of the carriers, and a series of gears also mounted to rotate at equal times and adapted to drive said cams, the latter having peripheral portions adapted to engage and shift said fabric elements from one carrier to the next, substantially as described.

6. In a fabric-weaving machine, the combination with holders for the warp or strand elements of the fabric, of carriers mounted to revolve upon axes coincident with said holders, of a series of holders for the web or mesh elements of the fabric, said carriers being adapted to engage at their peripheries said web-element holders, and a series of cams adapted to revolve about the axes of the carriers and to engage said web-holders at predetermined points of their revolution, whereby to shift or transfer said holders from one carrier to the next adjacent carrier throughout the series, substantially as described.

7. In a shifting mechanism for wire-weav-

ing fabric machines, the combination with a series of revolving carriers, of a series of strand-wire carriers or holders, and a series of web or mesh wire holders, the former being mounted in line with the axes and the latter eccentric to the axes of the carriers, and suitable gearing for driving the carriers in equal times and suitable gearing for driving the cams in equal times, whereby the web or mesh wires may be shifted from one strand-wire to the other and successively carried around the same, substantially as described.

8. In a wire-weaving machine, the combination with a series of strand-wire holders rotatably mounted in parallelism, of a series of web-wire holders also mounted in parallelism to each other and to the strand-wire holders but eccentric thereto, of a series of carriers for each end of the web-wire holders, said carriers being mounted to rotate upon axes in line with the axes of the strand-wire holders and adapted to engage at their peripheries the web-wire holders, and means for simultaneously shifting the series of web-wire holders from one carrier to another throughout the series at predetermined times, substantially as described.

9. In a shifting mechanism for wire-weaving machines, the combination with a series of revolving carriers geared to rotate in equal times, of a series of cams, one for each carrier, and a series of gears one for each cam, mounted concentric to the axes of the carriers but rotatably independent thereof, of a series of gears driven in unison with the carriers, and a series of gears driven therefrom in equal times, but with a varying rate of speed, said last-mentioned series of gears being adapted to drive the cam-gears and thereby the cams, substantially as described.

10. In a wire-weaving machine, the combination with a series of strand-wire holders, of a series of web-wire holders, a series of carriers for carrying the web-wire holders around the strand-wire holders, means for shifting the web-wire holders from one carrier to the next, and a coiling mechanism comprising a series of split twister-heads or coilers, one member of each coiler being adapted to be shifted to and have successive matching relation with an adjacent coiler, gearing for driving the carriers constantly and gearing for driving the coilers intermittently, but at a higher rate of speed, whereby time is allowed for the shifting of the coiling mechanism, substantially as described.

11. In a wire-weaving machine, the combination with constantly-running means for carrying the web-wires around the strand-wires, and means for shifting the web-wire carriers from one strand-wire to another, of an intermittently-driven coiling mechanism, substantially as described.

EDWARD F. SHELLABERGER.
